GRINDING WHEEL TRUING DEVICE FOR
GRINDING MACHINES, MORE ESPE-
CIALL FOR THREAD GRINDING MA-
CHINES

Fernand Turrettini, Bellevue-Geneva, Switzerland, assignor to Societe Genevoise d'Instruments de Physique, Geneva, Switzerland, a firm of Switzerland

Application October 22, 1947, Serial No. 781,458
In Switzerland November 13, 1946

5 Claims. (Cl. 125—11)

1

The object of the present invention is a grinding wheel truing device for grinding machine, more especially for a thread grinding machine.

Numerous devices serving this purpose are known. Some of them are based on the principle of a cam of suitable shape imparting to a diamond point a reciprocating movement perpendicular to the axis of the work piece, this reciprocating movement being synchronised with a continuous translation movement of the diamond in a direction parallel to said axis, in such a way that, by the combination of these two movements, the diamond point describes the required profile on the active edge of the grinding wheel.

This system has the drawback that the operation of the shape of the diamond point, as an effect of the natural wear, modifies rapidly the profile obtained on the grinding wheel.

Other truing apparatuses comprise a stationary device provided with a diamond following a path parallel to the flanks of the grinding wheel edge, this movement being completed by a pivoting movement about an axis approximately tangent to the grinding wheel edge, in such a way that the diamond, after having trued one flank, passes on to the other flank by following the arc of circle connecting the two flanks of the grinding wheel. This system has the drawback that it is very difficult to adjust the pivoting angle of the device for obtaining an accurate profile angle on the grinding wheel.

There are also truing devices comprising two movable diamond-holder slides, forming between them a set or adjustable angle, and which are operated by a common control member; the diamonds true alternately the faces of the grinding wheel in opposite direction. The adjustment of the angular position of the slides to obtain the correct angle of the grinding wheel profile, is realised in these systems by means of very complicated and not over-precise mechanisms.

The device according to the invention avoids the drawbacks involved in the known systems. It is characterized by two diamond-holder slides movable perpendicularly to the axis of the work piece, on a common carriage, one of said slides presenting a solid wedge bearing on a roller whose shaft is mounted at right angle on a guideway on which said carriage is slidable in a direction parallel to the axis of the work piece, said slides being operatively connected to a common swinging control member for reciprocating movement in opposite direction to one another, whereby the carriage receives a movement on its guideway in synchronism with that of the slides, and at right

2

angle thereto, the angle of the wedge being half that which is formed between the flanks of the grinding wheel, the whole operating in such a way that the two diamonds cut simultaneously both flanks of the grinding wheel under the action of the reciprocating movement imparted to the control member.

The device according to the invention has thus the advantages that both flanks of the grinding wheel are cut simultaneously, that the diamonds always attack the grinding wheel by the same spot of their point, and that the angle to be formed between the flanks of the grinding wheel is determined by the angle of the wedge, which is a mechanical part of simple shape, which it is easy to manufacture with precision. This wedge can be mounted removably, in order to allow truing a grinding wheel at 60° for the SI profile, and then to pass to the Acme profile, simply by replacing the 30° wedge, by a 15° one.

The attached drawing represents by way of example an embodiment of the present invention.

Fig. 1 is a plan view thereof.

Figs. 2, 3 and 4 are cross-sections along II—II, III—III and IV—IV of Fig. 1.

On the drawing, and especially in Fig. 1, I shows the grinding wheel, 2 and 3 its two flanks, 4 and 5 the cutting diamonds operating respectively on these flanks, 6 and 7 the setting of these diamonds, while 8 and 9 show their mounting on the slides 10 and 11, these slides are provided with racks 12 and 13 meshing with a pinion 14 for imparting to the slides a reciprocating movement in opposite direction to one another; 15 is the shaft of this pinion.

The wedge 16, the angle of which determines half the angle comprised between the flanks of the grinding wheel, is secured on the slide 10 by means of screws 17 and 18. The oblique side of the wedge bears on a roller 17' pivoted at 18'. A tightly sealed casing 19 surrounds the whole device. Apertures 68 and 69 are provided in the casing for letting out the end of the slides 10 and 11 with their mountings 8 and 9.

Fig. 2 shows how the slide 10 can move on the face 20 of a guideway 21 secured by screws 22 and 23 on the carriage 27. To the right and to the left of the part of the guideway 21 by which it is secured on the carriage 27, this guideway comprises extensions 24 and 24', of reduced thickness, the inner surfaces 28 and 28' of which cooperate with retaining plates 25 and 26 in preventing the slide 10 from being lifted. These retaining plates are secured on the lower face of the slide 10.

The carriage 27 is movable on the guideway

29, on which it is guided by its faces 30, 31 and 32, which fit on the corresponding faces of the guideway 29. Retaining plates 35 and 36, secured on the carriage 27, cooperate with the faces 33 and 34 of the guideway 29.

Fig. 3 shows that the slide 11 is mounted substantially in the same way as the slide 10. In addition to the parts already described, one notices that the wedge 16 is set in a groove 37, in order to define accurately its position, and that the guideway 21 and 21' are also secured by means of screws 39 and 39' in grooves 38 and 38' formed in the carriage 27, thus ensuring the parallelism of the guideways.

Furthermore the pivot 18' of the roller 17' is shown being part of a shaft 48 secured at 40 on the guideway 29 by means of screws 41, and the carriage 27 is guided on the guideway 29 by means of retaining plates 42 and 43 secured on the carriage 27 by means of screws 44.

Further, a spring 45, bearing on the one hand on the bottom of a recess 46 formed in the guideway 29 and on the other hand on a part 47 of the carriage assembly 27, tends to push the latter to the right, to make sure that the roller 17' bears on the wedge 16. The shaft 48, secured on the guideway 29 and carrying the roller 17', traverses the carriage 27 through an aperture 49 which is large enough to allow for the movement of the carriage 27 on the guideway 29.

The guideway 29 is secured on a base 50 by means of the screws 51 and 51'; a plate 52 is interposed between 29 and 50 to meet the retaining plates 42 and 43, 35 and 36.

The lower surface 53 of the base 50 is cylindrically shaped, in order to allow tilting of the apparatus on the frame 54, for truing on a grinding wheel, profiles contained in a plane which is oblique in respect with the axis of the grinding wheel. The base 50 is held on the frame 54 by means which are not shown on the drawing.

Fig. 4 shows especially the control member of the slides 10 and 11. The shaft 15 of the pinion 14 is held in a bushing 56 secured by the screws 57 on the carriage 27. This shaft extends through the casing 19 and carries a hub 59 provided with a hand lever 58; this hub is removable from the shaft 55 in order to permit removing the casing 19 and thus enable replacing the wedge 16 by another one having a different angle. Abutments 60 and 60' (Fig. 1) are formed in the casing 19 for limiting the possible travel of the slides 10 and 11 under the action of the pinion 14.

The operation of this apparatus is as follows:

Upon actuation of the hand lever 58, the diamond-holder slides 10 and 11 are moved in opposite directions. The axial movement of the slide 10, which carries the wedge 16 bearing against the immovable roller 14, causes the perpendicular movement of the carriage assembly 27, with all what it carries, in consequence of the obliquity of the wedge. The diamond 4 must follow an oblique path parallel to the edge of the wedge 16 while the diamond 5 must follow a path in the opposite direction, symmetrically oblique in respect with the plane of the grinding wheel. Both diamonds follow simultaneously both flanks of the grinding wheel in opposite direction to one another, and their direction of movement is reversed when the hand lever 58 is being brought back to its starting point after having reached the end of its swing.

The above described truing device thus provides for the truing of grinding wheels having a triangular profile. In several thread systems,

and for instance in the Acme system, the top of the triangle is cut off by a truncation. An additional diamond 62 enables carrying out this truncation on the grinding wheel. This diamond 5 is borne by an arm 63 ended by a control handle 64 and pivoted on a shaft 65 in a bearing 66 secured on the casing 19. An adjusting screw 67 is provided for setting the distance separating the truncation from the top of the triangle formed by the paths of the diamonds 4 and 5.

What I claim is:

1. In a grinding wheel truing device for grinding machine, especially for a thread grinding machine, a base secured on the machine frame, a guideway secured on said base, a carriage slideable on said guideway, a slot in said carriage, a shaft secured at right angle on said guideway and extending through said slot, a roller pivoted on said shaft, two diamond-holder slides slideable in said carriage at right angle to the direction of said guideway and operatively connected to a common swinging control member for reciprocating movements of said slides in opposite direction to one another, a wedge secured on one of said slides and bearing by its oblique edge on said roller, and a spring operatively connected between said guideway and said carriage and supplying contact pressure between wedge and roller, the angle of the wedge being half that to be formed between the two directions of displacement of both diamonds, whereby both diamonds cut simultaneously both flanks of the grinding wheel under the action of a swinging movement given to the common control member.

35 2. In a grinding wheel truing device for grinding machine, especially for a thread grinding machine, a base secured on the machine frame, a guideway secured on said base, a carriage slideable on said guideway, a slot in said carriage, a shaft secured at right angle on said guideway and extending through said slot, a roller pivoted on said shaft, two diamond-holder slides slideable in said carriage at right angle to the direction of said guideway and operatively connected to a common swinging control member for reciprocating movement of said slides in opposite direction to one another, a wedge secured on one of said slides and bearing by its oblique edge on said roller, and a spring operatively connected between said guideway and said carriage and supplying contact pressure between wedge and roller, the angle of the wedge being half that to be formed between the two directions of displacement of both diamonds, whereby both diamonds cut simultaneously both flanks of the grinding wheel under the action of a swinging movement given to the common control member, and a third diamond mounted on said carriage for alternating movement in a plane perpendicular to the bisector of said angle to be formed between said directions of displacement for carrying out a truncation in the triangle formed by the two flanks of the grinding wheel edge.

3. In a grinding wheel truing device for grinding machine, especially for a thread grinding machine, a base secured on the machine frame, a guideway secured on said base, a carriage slideable on said guideway, a slot in said carriage, a shaft secured at right angle on said guideway and extending through said slot, a roller pivoted on said shaft, two diamond-holder slides slideable in said carriage at right angle to the direction of said guideway and operatively connected to a common swinging control member for reciprocating movements of said slides in opposite direction to

one another, a wedge secured on one of said slides and bearing by its oblique edge on said roller, and a spring operatively connected between said guideway and said carriage and supplying contact pressure between wedge and roller, the angle of the wedge being half that to be formed between the two directions of displacement of both diamonds, whereby both diamonds cut simultaneously both flanks of the grinding wheel under the action of a swinging movement given to the common control member, and a third diamond mounted on said carriage for alternating movement in a plane perpendicular to the bisector of said angle to be formed between said directions of displacement, for carrying out a truncation in the triangle formed by the two flanks of the grinding wheel edge.

4. In a grinding wheel truing device for grinding machine, especially for a thread grinding machine, a base secured on the machine frame, a guideway secured on said base, a carriage slidable on said guideway, a slot in said carriage, a shaft secured at right angle on said guideway and extending through said slot, a roller pivoted on said shaft, two diamond-holder slides slidable in said carriage at right angle to the direction of said guideway and operatively connected to a common swinging control member for reciprocating movement of said slides in opposite direction to one another, a wedge secured on one of said slides and bearing by its oblique edge on said roller, and a spring operatively connected between said guideway and said carriage and supplying contact pressure between wedge and roller, the angle of the wedge being half that to be formed between the two directions of displacement of both diamonds, whereby both diamonds cut simultaneously both flanks of the grinding wheel under the action of a swinging movement given to the common control member, said wedge be-

ing mounted removably on its supporting slide.

5. In a grinding wheel truing device for grinding machine, especially for a thread grinding machine, a base secured on the machine frame, a guideway secured on said base, a carriage slidable on said guideway, a slot in said carriage, a first shaft secured at right angle on said guideway and extending through said slot, a roller pivoted on said first shaft, two diamond-holder slides slidable in said carriage at right angle to the direction of said guideway, two racks secured on the diamond-holder slides respectively, a second shaft secured at right angle on said carriage, a pinion secured to said second shaft and meshing with both racks, a hand lever secured to said second shaft, for reciprocating said slides in opposite direction to one another, a wedge secured on one of said slides and bearing by its oblique edge on said roller, and a spring operatively connected between said guideway and said carriage for pressing said wedge against said roller, the angle of the wedge being half that to be formed between the two directions of the displacement of both diamonds whereby upon reciprocation of said hand lever both diamonds cut simultaneously both flanks of the grinding wheel.
